(57) **CLAIM**

The ornamental design for a “transverse and vertical rotary vise”, as shown and described.

DESCRIPTION

FIG. 1 is a top, front and right side perspective view of a “transverse and vertical rotary vise”, showing my new design; FIG. 2 is a front elevational view thereof; FIG. 3 is a rear elevational view thereof; FIG. 4 is a right side elevational view thereof; FIG. 5 is a left side elevational view thereof; FIG. 6 is a top plan view thereof; FIG. 7 is a bottom plan view thereof; FIG. 8 is a top, front and right side perspective view of a “transverse and vertical rotary vise”, showing my new design in an open position; FIG. 9 is a front elevational view thereof; FIG. 10 is a rear elevational view thereof; FIG. 11 is a right side elevational view thereof; and, FIG. 12 is an enlarged right side perspective view thereof.
